Specification of Letters Patent.

Patented Feb. 7, 1922.

Application filed July 5, 1919. Serial No. 308,779.

To all whom it may concern:

Be it known that I, MILTON H. BALLARD, a citizen of the United States, residing at Lynn, in the county of Essex and State of Massachusetts, have invented certain Improvements in Presses, of which the following description, in connection with the accompanying drawings, is a specification, like reference characters on the drawings indicating like parts in the several figures.

This invention relates to presses in which the presser members are relatively movable into different operative relations to each other, and particularly to presses designed to cut sheet material by the use of freely movable dies.

Presses of the type just referred to are advantageously constructed with presser members having different presser surface areas and in the preferred construction a movable presser member having a presser surface area considerably less than a stock supporting bed is movable over said bed to bring it into operative relation to a die placed upon different portions of the stock which is supported upon the bed. As these machines are commonly constructed, the movable presser member must be moved into operative position by force exerted directly by the operator, with the result that a very considerable part of the labor incidental to cutting operations is expended in overcoming the inertia of the relatively heavy presser member in moving it to the desired operative position over the die and in moving it away from the die after a cutting operation.

It is an object of the invention to provide improved power means for moving the presser member into and out of operative position over the cutting bed.

In one aspect the invention comprises an organization in which the power means for moving the movable presser member is operatively connected to the said member by flexible means, one of the numerous advantages of such a construction being that said power means may be readily embodied in machines or attached to existing machines in any desired location. In a preferred form of the invention the described flexible means comprises a cable having a portion arranged to run in opposite directions according as it is desired to move the presser member to or from any selected position.

In another aspect the invention comprises

an organized machine in which means is provided for controlling the power means for relatively moving the presser members so located below the presser member as to be readily accessible to the operative. In a practical form of the invention the said means controls also the actuation of the machine to effect the pressure applying movements of the presser member.

An important feature of the invention comprises improved means for checking the lateral movement of the presser member when it is descending toward the work so that the presser member may be moved as rapidly as desired in a direction to place it over the work and the tripping lever actuated to cause a pressure applying operation of the pressure member while it is still moving laterally, the checking means operating to stop the lateral movement as described so that the work is not struck a glancing blow. Were it not for the provision of such means in the organization of the improved machine it would be impossible to operate the machine with the rapidity and efficiency now attained. In a preferred form of the invention the checking means or brake mechanism comprises means mounted independently of the presser member and arranged to engage the presser member directly for preventing lateral movement of the member at a predetermined point in the downward movement of the presser member.

In one type of press the presser member is mounted at one side of the stock supporting bed upon a post which is vertically reciprocable to effect the pressure applying operations of the presser member, the presser member being arranged to swing about the axis of the post into and out of operative position above the bed. In operating with this machine, the object to be operated upon is often located well out toward the free end of the presser member with the result that the leverage through the presser member is so great that upon a pressure applying operation the post and frame of the machine spring away from the work supporting bed with the free end of the presser member tipped upwardly. Hence, it occasionally happens that work positioned at the free extremity of the presser member is not operated upon properly due to the springing of the frame as just described. It is an object of this invention to provide improved

means for preventing tipping of the presser member away from the work supporting bed during pressure applying operations, the said means operating also to prevent bending 5 or other distortion of the post and its supporting frame. In a preferred embodiment of the invention there is provided means operated to act on the presser member for preventing tipping of the presser member in 10 the manner described, the construction being preferably such that a supporting member is arranged to engage the presser member just as the latter is coming into contact with the work to prevent tipping of the presser member 15 away from the work, a marked advantage of such a construction being that the presser member is independent of the supporting member and freely movable relatively thereto during the positioning of the presser member 20 over the work wherever the latter may be located on the work supporting bed.

In a preferred form of the invention the means for checking the lateral movement of the presser member is combined with the 25 means for preventing the tipping of the presser member away from the work supporting bed in a single mechanism which is particularly simple in construction and efficient in operation. In the illustrative construction 30 the said mechanism comprises a member which is independently operated so as to move with the presser member but out of contact therewith during the first part of the pressure-applying movement of the 35 presser member and then to move relatively to the presser member during the latter part of the pressure-applying movement gradually to check lateral movement of the presser member and finally to check completely such 40 lateral movement and afford perfect support to the presser member so that no tipping movement thereof can take place.

Another feature of importance resides in the provision of means for supporting the 45 presser member in such manner that there is no tendency for the presser member to tip or turn about an axis extending longitudinally thereof during the pressure-applying operation. In the illustrative construction, 50 the presser member is supported intermediate between its ends on a supporting post, or has a portion extending in line with the pressure-applying portion and on the other side of the supporting post, and 55 is provided with a support for said extending portion so constructed and arranged with respect to the supporting post and the work supporting bed that a line drawn through the center of gravity of the object 60 being pressed and intersecting said support passes also through the axis of the supporting post, such a construction and arrangement of parts obviously providing against any tendency of the presser member to tip 65 or turn in the manner described.

In a machine organization in which one presser member is movable laterally with respect to another so that the movable member may be moved into operative position over the work and then away from such 70 position after a pressure applying operation, it is desirable to provide means to assist the operator in overcoming the inertia of the presser member in moving it away from operative position, thus lessening materially 75 the labor incidental to the carrying-on of pressing operations. It is an object of the invention to provide improved means for the purpose indicated which shall be automatically operative and therefore useful in 80 machines which provide power means for moving the presser member into operative position as well as in machines in which no such power moving means is provided. In a preferred form of the invention, the said 85 automatic means for moving the presser member away from operative position comprises a clutch for connecting the presser member with said automatic means, controlled by said presser member, and so arranged as not to interfere with the lateral movement of the presser member to operative position.

Other features and objects of the invention will be apparent from the following 90 detailed description and will be pointed out in the claims.

In the drawings:—

Figure 1 is a view in side elevation of the illustrative embodiment of my invention; 100

Fig. 2 is a detail view of a check device used in connection with the power mechanism for moving the presser member;

Fig. 3 is a front view of the illustrative machine; 105

Fig. 4 is a detail view of a lever centering device;

Fig. 5 is a plan view of the machine from above;

Fig. 6 is a view partly in section of a detail of the power mechanism for swinging the presser member; 110

Fig. 7 is an enlarged detail view of part of the clutch tripping mechanism;

Fig. 8 is a detail view partly in section of a cone clutch retriever mechanism operative in connection with the presser member; 115

Fig. 9 is a detail view partly in section of the work support adjusting means; and

For. 10 is a fragmentary view of the connections between the main shaft and the presser member for supporting and operating the presser member, and of operative connections for the power means for moving the presser member laterally over the 120 work supporting bed.

In the illustrative machine there are provided a work support 12 and a presser member 14 movable laterally over the work support into operative position above work 130

placed in selected position on the work support and movable toward and from the support in pressure applying operations. In order that the presser member may move laterally over the work supporting bed it is mounted on a post 16 which, in the preferred construction, is non-rotatable, the presser member being arranged to rotate on the post and the latter being reciprocable vertically to carry the presser member toward and from the cutting bed. In the construction shown, the presser member has an extension 18 in line with the pressure applying portion 14, a support 20 being provided to co-operate with the extension 18 in affording support for the presser member during pressure applying operations upon the work, thus relieving the post and the frame of the machine from any tendency to bend or to become distorted because of the strains and stresses incident to the application of great pressure on the work by the overhanging presser member 14. This support 20 is normally spaced about $\frac{3}{2}$ " from the lower surface of the extension 18 and is arranged to move downwardly with the extension and to come into firm supporting relation thereto just as the presser member contacts with the work, which may be a die and the material to be cut thereby. Referring especially to Figs. 1 and 10, it will be observed that the main shaft 22 is provided with an eccentric 24 embraced by the eccentric strap 26 having secured thereto at 28 a link 30 pivotally connected at 32 to the lower end of the post 16. The same shaft is provided with a second eccentric 34 around which passes the eccentric box 36 to which is attached the lower end of a slide bar 38 which carries at its upper end the support 20 referred to above, a gib 39 being interposed between the member 38 and the box 36. The eccentrics 24 and 34 are so related to each other as to hold the presser member extension 18 slightly spaced (approximately $\frac{3}{2}$ ") from the support 20 when the machine is at rest. Upon rotation of the shaft through 90° the presser member extension is brought into contact with the support 20 and, as the presser member is coming into contact with the die, that is, as the shaft is approaching 180° in its rotation, the eccentric for the post 16 has moved the presser extension 18 $\frac{3}{2}$ " further than the support 20 in the downward direction during the last 90° of rotation of the shaft so that the presser extension 18 is firmly clamped on the support 20 as the presser member strikes the die and hence any tendency of the presser member to tip about its horizontal axis of support is prevented by the support 20. The supporting member 20 has the further function, and an important one as will be made clear in a discussion of the operation of the machine, of preventing further lateral movement of the presser member just as it is about to come into contact with the die, the purpose being to prevent the presser member from striking a glancing blow on the die. Since the extension 18 on the presser member comes into contact with the support 20 at the end of a 90° rotation of the shaft and in the continued rotation of the latter is pressed more and more firmly against the support, the latter acts as a brake or checking means to prevent further lateral movement of the presser member from and after a predetermined point in the downward movement of the presser member. It will be apparent that the supporting member 20 is the important element of a single mechanism which operates not only to check lateral movement of the presser member but to prevent tipping of the latter away from the work supporting bed. In order that the support 20 may co-operate with the presser member in all positions of the latter relatively to the cutting bed, the said supporting member 20 is formed on an arc the center of which is in the axis of the post 16 as will be clear from an inspection of Fig. 5 of the drawings. In this connection, attention is called to the fact that the presser member, the cutting bed 12 and the support 20 are so related to each other that wherever the presser member 14 is located with respect to any selected portion of the cutting bed, a line passing through the center of gravity of the die being operated upon and through the axis of the post 16 will fall within the ends of the arcuate support 20 so that there is no tendency for the presser member to turn about an axis extending longitudinally thereof. In other words, no matter in what position the presser member is operating, there will be no opportunity for twisting or other torsional strains to develop which would tend to distort or damage the presser member or the machine frame.

Means is provided for swinging the presser member by hand into any desired position with respect to the cutting bed and for operating the clutch mechanism whereby the presser member is caused to apply pressure upon the die, the said means comprising preferably a lever 40 having a handle 42 and pivoted at 44 to the presser member, the rear portion 46 of the lever being formed upon the arc of a circle and arranged to be engaged by the upper end 48 of a clutch tripping mechanism comprising parts mounted in the presser member to move therewith and shown in detail in Fig. 7 of the drawings. The mechanism for connecting the lever 40 with the clutch tripping lever 50 is preferably of such a construction that only one reciprocation of the presser member can take place upon actuation of the lever 40. In other words, the lever 40 must be actuated by the operator each time that

a pressure applying operation on the die is desired so that the lever 40 must be depressed and then released before a second reciprocation of the presser member can 5 take place. A preferred construction for ensuring this manner of operating the machine is shown to comprise a lever 52 having an extension 54 to engage normally over the upper surface of the part 46 of the lever 40, the said lever 52 being pivoted at 10 56 to a collar 58 fast on the rod 60, a spring 62 being connected at its ends to studs or pins 64 and 66, located respectively on the collar 58 and on the lever 52 above the pivot 15 point 56 of the latter and tending to keep the extension 54 of the lever constantly in contact with the portion 46 of the operating lever 40. Mounted in an upper floor 67 of the presser member extension 18 is an adjustable bolt 68 having thereon a slidable sleeve and collar 70 arranged to be engaged by an arm portion 72 of the lever 52, the said portion 72 being slotted at 74 to embrace loosely the sleeve member 70. Mounted 20 on the lower end of the rod 60, which is guided in bearings in floors of the presser extension 18, is a hook member 76 arranged to engage the under surface of an arcual member 78 having beveled end portions at 25 80 and centrally mounted upon the upper end of the rod 82 which is slidably pivoted at its lower end in a bifurcated portion 84 of the clutch operating lever 50. Adjustably mounted on the rod 60 is a second 30 collar 86 carrying an adjustable pin or stud 88, the arrangement being such that the spring 90 which is connected to the upper collar 58 on the rod 60 and to a pin or hook 92 in the lower floor 94 of the presser member 35 extension 18, constantly tends to hold the lower end of the adjustable pin 88 in contact with the floor portion 94 of the presser member extension 18. Upon actuation of the lever 40 the rear end portion 46 of the same moves upwardly carrying the lever 52 with it and lifting the rod 60 which carries the rod 82 upwardly through the hook 76 engaging under the arcual member 78, and thus actuating the clutch lever 50. 40 Practically at the termination of the upward movement of the end portion 46 of the lever 40 the portion 54 of the lever 52 slides off of the upper surface 96 of the end portion 46 and engages with the rear curve 45 surface of the end portion 46 against which it is held by the spring 62. This tipping of the lever 52 is caused by the sliding collar member 70 striking against a shoulder 97 on the bolt 68 after which the lever 52 turns 50 about 68 as a fulcrum until the end 54 slips off of the lever 46. When the extension 54 of the lever 52 drops off of the surface 96, the lever and the connected rod 60 are moved downwardly by the spring 90, before described, and thus the lever 40 must be re- 55 leased before the clutch operating rods 60 and 82 can again be actuated to trip the clutch. When the lever 40 is released the rear end portion 46 moves downwardly as the front portion of the lever moves upwardly under the action of the spring 98 (Fig. 1), thus re-engaging the extension 54 of the lever 52 with the upper surface 96 of the lever end 46. Since the lever 52 and its connected rod 60 are carried by the 60 presser member extension 18, as the latter swings about the axis of the post 16 a sliding connection must be provided between the lower end of the rod 60 and the upper end of the rod 82 thus accounting for the 65 arcual plate or member 78 which, as will be observed upon inspection of Fig. 1, is stationary in the horizontal plane, being mounted for vertical sliding movement in the frame of the machine and in connection 70 with the forked end of the lever 50. Inasmuch as the presser member 14 may be swung to one side entirely clear of the cutting bed 12 in which position the hook 76 would no longer be engaged under the 75 plate 78, the latter is provided at its ends with the beveled surfaces 80 as before described in order to cause the hook 76 to re-engage with the under surface of the plate 78 when the presser member 14 is 80 returned to position over the bed. The arrangement just described is such that if the operative should depress the starting lever 40 while the presser member is at one side of the cutting bed there would be no actuation of the clutch operative lever 50 since the hook 76 is disengaged from its co-operating member. If, however, the lever 40 be maintained in depressed position while the presser member is swung into position over 85 the cutting bed the hook 76 will re-engage with the plate 78 and thus cause tripping of the clutch operating lever 50 and instant operation of the machine as the presser member returns to operative position over 90 the bed. In connection with the means above described for ensuring a single reciprocation of the presser member upon actuation of the lever 40, the main shaft 95 22 of the machine is provided with a one 100 revolution clutch preferably, though not necessarily, of the type shown in the patent to Arthur Bates No. 921,503, granted May 11, 1909, the said clutch mechanism being housed within a casing extending inwardly 105 from the power pulley 100. 110 In the illustrative machine, power means is provided for moving the presser member into and out of operative position over the cutting bed. This is especially desirable in 115 the present instance since the presser member together with its extension 18 is a relatively heavy member, the whole construction being designed particularly for use in the cutting of extra heavy sheet material. The 120 125 130

power means for moving the presser member comprises preferably a cable attached to the presser member and driven selectively in either one of two directions at the will of the operator to effect movement of the presser member in the desired direction. In the construction shown, the cable 102 has its ends 104 and 106 attached to a cylindrical member 108 fixedly attached to the lower surface of the presser member 14. (See Figs. 1 and 3 of the drawings.) One of the cable end portions is passed one or more times around the drum member 108 and from there passes over an idle pulley 110 mounted in a bracket 112 at the upper left hand side of the machine frame and thence to a second idle pulley 114 mounted in a similar bracket 116 directly below the first bracket and passes thence over a drum 117 turning freely on a bearing 118, (Fig. 6) the cable passing from the said drum around an idle pulley 120 (Fig. 3) carried by a bracket 122 and from there to a second drum 124 also turning freely on a bearing 126. From the second drum the cable passes over an idle pulley 128 and from there around the drum member 108 on the presser member 14 to which its end is fixedly attached as before stated. In order to cause the cable to run first in one direction and then in the other, it is necessary only to operate the drums 117 and 124 selectively in the desired directions and this is accomplished by connecting the drums one at a time to the constantly rotating shaft 130. In the construction shown, the means for thus connecting the drums to the shaft comprises a double cone clutch consisting of a clutch member 132 by which the drum 117 is clutched to the shaft 130 and a clutch member 134 by which the drum 124 is similarly operatively connected to the shaft. Normally the clutch members are disengaged from their respective drums but upon endwise movement of the shaft 130 either clutch member, as desired, is caused to engage with its respective drum. Endwise movement of the shaft 130 may be secured through any desired means, that shown comprising a sleeve 136 freely rotatable with respect to the shaft 130 and screw threaded exteriorly to engage with corresponding screw threads in a nut 138 fixedly secured in the frame of the machine. The sleeve 136 is fixedly engaged by a member 140 having a handle or arm 142, collars 144 and 146 fixedly attached to the shaft 130 being arranged to engage with the handle member 140 and with the sleeve 136, respectively, to hold the same against endwise movement on the shaft while permitting the shaft to rotate independently of the combined sleeve and handle member. If the handle 142 be moved in either direction the sleeve 136 is caused to turn in the fixed nut 138 and thus to move endwise in said nut carrying with it in its endwise movement the shaft 130. Thus, if the shaft is moved to the right in Fig. 6 the clutch member 132 is caused to engage with the drum 117 and if the shaft 130 be moved to the left, in the same figure, the other clutch member 134 is caused to engage with its drum 124 whereby the cable is caused to run in the desired direction, the drum, which at the time is not clutched to the shaft, turning freely with the other drum and cable in the direction determined by the clutched drum. The endwise movable shaft 130 is driven constantly in one direction by connections from the main shaft 80 of the machine, the said connections providing preferably an endless cable or belt 148 passing around a pulley 150 fixed to or integral with the power pulley 100 and over two idler pulleys 152 and 154 and thence over a pulley 156 intermediate of the other two and fixed to a shaft 158 having fixedly attached thereto a worm 160, the worm being in mesh with a worm gear 162 splined on the endwise moving shaft 130. In order that the shaft 130 may be shifted endwise at the will of the operator, the arm 142, connected to the sleeve 136 (Fig. 6), as described above, is connected by a link 164 (Fig. 3) with the lower end of a lever 166 pivoted at 168 to a bracket on the frame of the machine and provided with a handle 170 upon movement of which to the right or left, in Fig. 3, movement of the arm 142 is produced to effect the desired endwise shifting of the shaft 130. In order that there may be no tendency to lock the shaft 130 against endwise movement through the interlocking threads on the sleeve 136 and the fixed nut 138, the pitch of these threads is made relatively steep so that slight rotative movement of the arm 142 causes the desired endwise shifting of the shaft to effect a clutching of either drum to the shaft, the construction and arrangement being such that a slight movement of the arm 142 in the reverse direction will move the double clutch to neutral position; that is, an intermediate position with both drums free of clutching engagement with their respective clutch members. While the power means for moving the presser member may be controlled by the handle 170, as just described, and then actuation of the machine to cause a pressure applying operation of the presser member be made dependent upon depression of the handle 42, a more efficient and satisfactory arrangement is comprised in the control of the power means for moving the presser member and the power means for causing pressure applying movements of the presser member through the actuation of a single manually controllable means. In the construction shown, the handle 170, by which the power means for moving the presser 139

member is controlled, is also connected in such manner as to control the power means for effecting reciprocation vertically of the presser member. Preferably, therefore, the lever 166 comprises two members 172 and 174 (Fig. 1) pivoted together at 176 and normally held in close relation by a spring pressed bolt 178 passing through both members, the arrangement being such as to permit the member 172 to be moved toward the right to a limited extent as shown in Fig. 1 and, upon such movement, the clutch lever 50 is operated through the connecting link 180 pivotally attached at one end to the upper end of the lever member 172 and pivotally and slidably attached at its other end to an arm 182 fixed to a stub shaft 184 which carries the lever 50. From the construction described, it will be clear that the handle 170 may be moved either to the right or left to control the power means for moving the presser member and then moved toward the operator to cause the throwing in of the clutch on the main shaft of the machine by which a single pressure applying reciprocation of the presser member is produced.

In order to hold the lever 166 normally in neutral position and to assist the operator in returning it to such position, there is provided a mechanism for thus centering the lever 166, the said mechanism comprising in the construction shown (Fig. 3) two spring pressed bolts or pins one of which is shown in detail in Fig. 4 of the drawings. As disclosed, each device comprises a casing 186 adapted to be fastened to the frame of the machine and carrying a bolt 188 normally pressed outwardly from the casing by a spring 190, the tension of which may be adjusted by the set screw 192. One of these spring devices is located on each side of the lever 166 with the spring pressed bolts engaging on opposite sides of the lever 166 below the pivot point 168 of the lever. Preferably there is also provided in connection with the cable means for moving the presser member, a buffer mechanism to limit yieldingly the swinging movement of the presser member in each direction. In the construction shown, this buffer mechanism comprises a casing 194 threaded upon the cable 102 and containing a block 196 pinned to the cable and springs 198 disposed one at each side of the block. The construction and arrangement are such that as the buffer device moving with the cable comes in contact with either bracket 112, 116 further movement of the cable in that direction is prevented not abruptly but yieldingly through the action of the spring in the casing located near the bracket with which the buffer is engaged. In other words, the brackets 112, 116 serve as abutments or fixed stops to limit, in co-operation with the buffer device or yielding

stop on the cable 102, the extent of the lateral movements of the presser member.

In connection with the presser member there is preferably provided a spring retriever mechanism which will operate to move the presser member away from the die as the presser member arises at the end of a pressure applying operation. Such a device will prove especially useful whenever the presser member is to be moved only a short distance to one side of the die as when the die is small and the light is coming from such a direction that no great movement of the presser member is necessary. Preferably this spring retriever mechanism comprises a cone clutch 200 fitting in a recess in the lower surface of the presser member 14 and surrounding the post 16 as disclosed in Fig. 8 of the drawings. The clutch does not normally engage the presser member so that the latter is free to be swung at all times toward operative position. Surrounding the post and holding the clutch member at the upper limit of its movement is a spring 202 having one end fastened to the frame which carries the post 16 and the other end securely attached to a sleeve member 204 which encloses the spring and is fixedly attached to the clutch member 200. The sleeve member 204 above referred to has a flanged engagement with a second sleeve member 206 which is screw threaded into a bracket or ring 208 fixedly secured to the frame surrounding said post. The construction and arrangement are such that as the presser member begins its descent the clutch member 200 is engaged with the presser member with the result that the spring 202 is wound up at the same time that it is being compressed. Hence as soon as the presser member commences to rise after a pressure applying operation, the spring begins to unwind and through the friction clutch engagement with the presser member causes the lateral movement of the presser member away from over the die. Clearly the extent of effective operation of the spring retriever mechanism thus described depends upon the speed with which the presser member is moved to operative position and to a tripping of the clutch before the presser member reached a position directly over the die so that the presser member is moving laterally toward the die at the time the clutch is tripped. In other words, the presser member must be moving downwardly toward the die at the same time that it is moving laterally toward the die in order to engage the cone clutch 200 and wind up the spring. Thus, if the presser member is being manually moved to operative position a premium is placed upon rapid work in moving the presser member. Otherwise, that is, with slow movement, there is no retrieving action as the presser member arises from the die.

In the preferred construction of the machine the presser member is mounted rotatably on the post 16 and there is neither vertical adjustment of the post nor of the presser member with respect to the work supporting bed or cutting block. Hence the work support itself is made adjustable to suit various thicknesses of work and to enable the machine to be operated with dies of various heights. In the construction shown, the frame of the machine is strengthened at the front thereof by a plurality of ribs, such as that shown at 210, to provide a strong support or base 212, in direct line with the work support slide 214 guided in ways formed in part by plates 215. Upon the support or base there rests a fixed nut 216 with which is engaged an exteriorly threaded post member 218 arranged to be turned in the nut by means comprising a worm 219 on a shaft 220 and a gear 222 at the upper end of a post 224 fixedly attached to the post member 218. Upon rotation of the hand wheel 226 the work support may be adjusted upwardly or downwardly as desired.

In view of the foregoing description, it is thought that no extended statement of the mode of operation of the machine is necessary. After work has been placed upon the table 12 and the die located on the work, the presser member is moved to operative position over the die and in the construction shown this movement of the presser member may be accomplished either manually by force exerted directly by the operator or by power means under the control of the operator. If the presser member is to be moved but a slight distance into position over the die, the operator may make use of the handle 42 to swing the presser member and then may cause a pressure applying movement of the presser member simply by depressing this handle. At his option, however, the operator may use the power means for moving the presser member under all conditions, in which case the handle 170 is moved, in the direction it is desired to move the presser member, to cause the engagement of the proper clutch and drum on the end-wise movable shaft as above described and thus move the presser member into position over the die and, as the presser member approaches the die, the same handle may be moved in a direction to trip the clutch on the main shaft and thus cause a pressure applying operation of the presser member. In this connection, it should be stated that the expert operator does not wait until the presser member is directly over the die before tripping the clutch, but in rapid operation of the machine the clutch is tripped as the presser member approaches the die since the die will not in any case be struck a glancing blow, as means is provided for preventing a blow of this kind, the said means being

found in the brake furnished by the support 20, as above described. As the presser member rises, it is moved laterally by the spring retriever mechanism provided that it has been moved into operative position 70 with sufficient speed. Otherwise, the operator moves the presser member away from over the die either manually or by the power means provided.

Having fully described my invention, 75 what I claim as new and desire to secure by Letters Patent of the United States is:—

1. In a machine of the class described, presser members relatively movable with respect to each other into different operative 80 positions and toward and from each other in pressure-applying movements, and means comprising a cable for causing relative movement of the presser members into and out of selected operative positions. 85

2. In a machine of the class described, a cutting bed, a presser member, a frame for movably supporting said presser member, power means, and flexible means for operatively connecting said power means with the 90 presser member for causing movement of the presser member into and out of operative position over the cutting bed.

3. In a machine of the class described, a cutting bed, a presser member, and means 95 comprising a cable for moving the presser member into or out of selected position over the cutting bed.

4. In a machine of the class described, a cutting bed, a presser member, power means, 100 and a cable for operatively connecting said power means with the presser member for moving the presser member into and out of operative position over the cutting bed.

5. In a machine of the class described, a cutting bed, a presser member, a post for carrying the presser member, a drum on the presser member, and means comprising a cable attached to said drum for rotating the presser member to move it into and out of 105 operative position over the cutting bed.

6. In a machine of the class described, a cutting bed, a presser member, power means for causing movement of the presser member in either direction to place the presser 110 member in different operative positions over the cutting bed, and means mounted below the presser member for controlling said power means.

7. In a machine of the class described, a cutting bed, a presser member, power means for causing lateral movement of said presser member, power means for causing pressure applying movement of the presser member, and a single means mounted below the presser member for controlling both said power means. 125

8. In a machine of the class described, a cutting bed, a presser member, a post for rotatably supporting the presser member, and 130

- power means comprising a cable for causing rotation of the presser member in either direction to place the presser member in operative position over the cutting bed.
5. 9. In a machine of the class described, a cutting bed, a presser member, a post for rotatably supporting the presser member over the cutting bed, power means for causing rotation of said presser member, and a cable 10 for connecting said power means with said presser member.
10. In a machine of the class described, a cutting bed, a presser member, a post for rotatably supporting the presser member, a 15 frame in which the post is mounted for reciprocation, power means for causing rotation of said presser member, and means extending upwardly at one side of the cutting bed in a position accessible to the operator 20 for controlling said power means to effect swinging movement of the presser member at the will of the operator.
11. In a machine of the class described, a cutting bed, a presser member mounted for 25 movement into and out of position over the cutting bed, power means for causing such movement of the presser member comprising a constantly driven shaft, a drum arranged to be driven by said shaft, and a cable wound 30 on said drum and operatively connected to the presser member to cause swinging movement of the presser member at the will of the operator.
12. In a machine of the class described, a cutting member bed, a presser member rotatably mounted for movement into and out of position over the cutting bed, and power 35 means for causing such movement of the presser member comprising a constantly rotating shaft and a cable operatively connected to said presser member and arranged to be connected to said shaft to run in opposite directions to cause movement of the presser member into or out of operative position 40 over the cutting bed.
13. In a machine of the class described, a cutting bed, a presser member, a post for rotatably carrying said presser member, and power means for causing rotation of said 45 presser member comprising a constantly rotating shaft, drums arranged to be driven selectively by said shaft, and a cable passing around said drums and operatively connected to said presser member.
14. In a machine of the class described, a cutting bed, a presser member, a post carrying said presser member for movement over the bed, power means for causing rotation of said presser member comprising a cable, and 55 means under the control of the operator for causing said cable to run in opposite directions to cause rotation of the presser member into or out of operative position over the cutting bed.
15. In a machine of the class described, a cutting bed, a presser member, a post supporting the presser member for movement over the bed, power means comprising a cable for causing rotation of the presser member in either direction, power means for 70 causing pressure applying movement of the presser member, and means under the control of the operator for controlling the direction of run of the cable and for causing the actuation of the presser member. 75
16. In a machine of the class described, a cutting bed, a presser member, a post for rotatably supporting the presser member, and power means for causing rotation of the presser member comprising a constantly rotating 80 shaft mounted for endwise movement, a cable operatively connected to said presser member and arranged to be connected to said shaft upon endwise movement of the latter, and means for returning the said shaft to 85 neutral position.
17. In a machine of the class described, a cutting bed, a presser member mounted for movement into and out of selected positions 90 over the cutting bed, power means for moving the presser member, and means located at one side of the cutting bed in a position accessible to the operator for controlling said power means to effect movement of the presser member at the will of the operator. 95
18. In a machine of the class described, presser members relatively movable with respect to each other into different operative positions and toward and from each other in pressure-applying movements, and means 100 comprising a flexible device for causing relative movement of the presser members into and out of selected operative positions.
19. In a machine of the class described, a cutting bed, a presser member, and means 105 comprising a cable having a portion constructed and arranged to run in opposite directions for moving the presser member into or out of selected position over the cutting bed. 110
20. In a machine of the class described, presser members relatively movable into and out of operative position, means for causing such relative movement of the presser members, and means comprising a stop associated 115 with said first-mentioned means for limiting the said relative movement of the presser members.
21. In a machine of the class described, presser members relatively movable into and out of operative position, means for causing such relative movement of the presser members, and means comprising a cable for limiting the said relative movement of the presser members. 120
22. In a machine of the class described, a cutting bed, a presser member, a post rotatably carrying the presser member, means for causing rotation of the presser member, and means for limiting the rotation of the 130

presser member comprising a cable connected to the presser member.

23. In a machine of the class described, a work supporting member, a presser member arranged to co-operate with said work supporting member, a supporting post upon which the presser member is directly mounted, and means operated to act on the presser member for preventing tipping of the presser member away from the work supporting member during pressure applying operations.

24. In a machine of the class described, a work supporting member, a presser member arranged to co-operate with said work supporting member, a frame, a supporting post for the presser member mounted in the frame, and means operating on the presser member and movable therewith for preventing bending of the post and the supporting frame away from the work supporting member during pressure applying operations.

25. In a machine of the class described, a work supporting bed, a presser member, a post carrying said presser member and vertically reciprocable to move the presser member toward and from said bed, and means independent of the post and presser member for preventing lateral displacement of the presser member during the pressure applying operations.

26. In a machine of the class described, a work supporting bed, a presser member, a post carrying said presser member and vertically reciprocable to move the presser member toward and from said bed, and means reciprocable with the post to support the presser member and post against lateral tipping displacement during the pressure applying operations.

27. In a machine of the class described, a work supporting bed, a presser member extending over the bed, a post for supporting the presser member intermediate of its ends and for effecting vertical reciprocation of the presser member, and means operated to act on the presser member to support the presser member and the post against lateral displacement of the presser member with respect to the bed during pressure applying operations.

28. In a machine of the class described, a work supporting bed, a presser member extending over the bed, a post for supporting and for effecting vertical reciprocation of the presser member, a main shaft, and means movable with the presser member and operated directly from the main shaft to support the presser member and the post against tipping of the presser member and lateral displacement of the post during pressure applying operations.

29. In a machine of the class described, a work supporting bed, a presser member, a post supporting the presser member, said

presser member having an arm extending in line with the presser member over the work supporting bed, and means co-operating with said arm for supporting the presser member against tipping movement away from the bed during pressure applying operations.

30. In a machine of the class described, a work supporting bed, a presser member, a post supporting the presser member, said presser member having an arm extending in line with the presser member over the work supporting bed, and a vertically reciprocable slide for supporting the presser member and its post against distortion during pressure applying operations.

31. In a machine of the class described, a work supporting bed, a presser member, a post for supporting and effecting vertical reciprocation of the presser member, and means mounted independently of the presser member and arranged to engage the presser member directly for preventing lateral movement of the presser member at a predetermined point in its pressure applying movement toward the work supporting bed.

32. In a machine of the class described, a work supporting bed, a presser member, a post for supporting the presser member and for effecting vertical reciprocations thereof, said presser member having an extension which projects from the post in a direction different from that of the presser member, and vertically reciprocable means co-operating with said extension to retain the presser member against lateral movement at a predetermined point in its pressure applying movement.

33. In a machine of the class described, a work supporting bed, a presser member, a post for supporting and effecting vertical reciprocation of the presser member, and means arranged in parallelism with the post and vertically reciprocable therewith for locking the presser member against lateral movement at a predetermined point in its pressure applying movement toward the work supporting bed.

34. In a machine of the class described, a work supporting bed, a presser member, a post for supporting the presser member and for effecting vertical reciprocations thereof, said presser member having arms extending on opposite sides of the post, and means co-operating with one of said arms to hold the presser member against lateral movement just as it is about to come into contact with the work in a pressure applying operation.

35. In a machine of the class described, a work supporting bed, a presser member over said bed, a post for supporting and effecting vertical reciprocations of the presser member, a main shaft for moving said post, and a member slideable in the frame of the machine and operated by said shaft for locking

the presser member against lateral movement at a predetermined point in its movement toward the work supporting bed.

36. In a machine of the class described, 5 a work supporting bed, a presser member above the bed, a post for supporting and effecting vertical reciprocations of the presser member, and a member arranged to contact frictionally with the presser member to operate as a brake against lateral movement of the latter.

37. In a machine of the class described, a work supporting bed, a presser member over said bed, a post for supporting and effecting 15 vertical reciprocations of the presser member, a main shaft for moving said post, a member slidable in the frame of the machine for locking the presser member against lateral movement just as it is about to come 20 into contact with a die in a pressure applying operation.

38. In a machine of the class described, a work supporting bed, a presser member above the bed, a post for supporting and effecting 25 vertical reciprocations of the presser member, a vertically movable member arranged to contact frictionally with the presser member to operate as a brake against lateral movement of the latter, and 30 a main shaft having eccentrics for operating the post and said vertically movable brake member.

39. In a machine of the class described, a work supporting bed, a presser member extending over the bed, a post for supporting 35 the presser member and for moving it toward and from said bed, a braking member arranged to engage the presser member to check lateral movement thereof just as the presser member is about to come into contact with the work, means for reciprocating 40 the post, and means for operating the braking member to move the same with the post during the first part of the descent of the presser member and then to move the braking 45 member relatively to the presser member to cause the braking action on the presser member just as the latter is coming into contact with a die on the work supporting bed.

40. In a machine of the class described, a work supporting bed, a presser member extending over the bed, a post for supporting the presser member and for moving it toward and from said bed, a braking member arranged to engage the presser member to check lateral movement thereof just as the presser member comes into contact with the die, a main shaft, an eccentric on the shaft 55 for reciprocating the post, and a second eccentric operating on the braking member to move the same with the post during the first part of the descent of the presser member and then to move the braking member 60 relatively to the presser member to cause the

braking action on the presser member just as the latter is about to come into contact with the work on the supporting bed.

41. In a machine of the class described, a work supporting bed, a presser member 70 movable toward and from the bed, a post for supporting the presser member and for effecting vertical reciprocations thereof, a frame for supporting the post, and mechanism interposed between the presser member and the frame for the post and automatically operative to return the presser member in a direction laterally of the die at the termination of the pressure applying operation.

42. In a machine of the class described, a work supporting bed, a presser member movable toward and from the bed, a post for supporting the presser member and for effecting vertical reciprocations thereof, and an automatic retriever mechanism for the 85 presser member comprising a clutch controlled by the presser member.

43. In a machine of the class described, a work supporting bed, a presser member 90 movable toward and from the bed, a post for supporting the presser member and for effecting vertical reciprocations thereof, a frame for supporting the post, and mechanism comprising a spring surrounding the 95 post and operative automatically to return the presser member in a direction laterally of the die at the termination of the pressure applying operation.

44. In a machine of the class described, 100 a work supporting bed, a presser member movable toward and from the bed, a post for supporting the presser member and for effecting vertical reciprocations thereof, and a retriever mechanism for the presser member comprising a cone clutch and a spring, said clutch being arranged to be forced into firm contact with the presser member by said spring as the presser member is moved toward the work supporting bed.

45. In a machine of the class described, a work supporting bed, a presser member movable laterally along the bed and also toward and from the bed in pressure applying operations, a shaft, clutch mechanism 115 for connecting said shaft to the source of power, a lever, and connections between said lever and said clutch mechanism constructed and arranged to trip the clutch mechanism and to become inoperative for a further 120 clutch tripping operation until said lever has been released by the operator.

46. In a machine of the class described, a work supporting bed, a presser member movable laterally along the bed and also 125 toward and from the bed in pressure applying operations, a shaft, clutch mechanism for connecting said shaft to the source of power, a manually operable lever mounted on the presser member, and connections 130

between said lever and said clutch mechanism comprising a member arranged to release or disconnect the lever after the tripping of the clutch and to reconnect the lever to the clutch mechanism when the lever returns to its normal or initial position.

47. In a machine of the class described, a work supporting bed, a presser member movable toward and from the bed, in pressure applying operations, a post for supporting the presser member and around the axis of which the presser member rotates in moving to different operative positions over the work supporting bed, and means constructed and arranged to prevent twisting or turning of the presser member about an axis extending longitudinally thereof.

48. In a machine of the class described, a work supporting bed, a presser member movable toward and from the bed in pressure applying operations, and laterally to different operative positions over the work supporting bed, and power means operating on the presser member for preventing a turning or twisting of the presser member about an axis extending longitudinally thereof.

49. In a machine of the class described, a work supporting presser member, a frame approximating in width the long dimension of the presser member and provided with ribs to form a strong supporting base, a slide substantially as wide as the frame and slidable in ways therein and carrying said presser member, and means for adjusting the slide with respect to the base.

50. In a machine of the class described, a work supporting bed, a presser member, a post for supporting the presser member and for effecting reciprocations thereof toward and from the work supporting bed, said presser member being movable about the axis of the post into and out of operative position over the bed, and a single means for checking the lateral movement of the presser member at a predetermined point in its movement toward the bed and for preventing tipping of the presser member away from the work supporting bed during pressure-applying operations.

51. In a machine of the class described, a work supporting bed, a presser member, a post for supporting the presser member and for effecting reciprocations thereof toward and from the work supporting bed, said presser member being movable about the axis of the post into and out of operative position over the bed, and means comprising a supporting member for checking the lateral movement of the presser member at a predetermined point in its movement toward the bed and for preventing tipping of the presser member away from the work

supporting bed during the pressure-applying operations.

52. In a machine of the class described, a cutting bed, a presser member having a drum portion, a post upon which the presser member is rotatably mounted, and means comprising a cable passing around the drum for rotating the presser member to move it into and out of operative position over the cutting bed.

53. In a machine of the class described, a work supporting member, a presser member arranged to co-operate with said work supporting member, a supporting post for the presser member, and means comprising relatively reciprocable members for supporting the presser member against tipping movement away from the work supporting member.

54. In a machine of the class described, a work supporting bed on the presser member movable laterally along the bed and also toward and from the bed in pressure applying operations, a shaft, clutch mechanism for connecting said shaft to the source of power, a lever connected to operate the clutch, a lever mounted on the presser member for controlling the presser member during its reciprocations in the various described directions, and connections between said levers operative to trip the clutch mechanism upon actuation of the last mentioned lever and to become inoperative for a further clutch tripping operation until the last mentioned lever has been released by the operator.

55. In a machine of the class described, a cutting bed, a presser member, a post upon which the presser member is rotatably mounted so as to be movable laterally over the bed into and out of selected operative positions, and power means under the control of the operator for swinging the presser member in the desired direction.

56. In a machine of the class described, a cutting bed, a presser member, a post upon which the presser member is rotatably mounted so as to be movable laterally over the bed into and out of selected operative positions, power means for causing reciprocations of the presser member toward and from the cutting bed, power means for swinging the presser member laterally over the cutting bed, and a single manually controllable member for controlling both said power means.

57. In a machine of the class described, a cutting bed, a presser member, a post upon which the presser member is rotatably mounted so as to be movable laterally over the bed into and out of selected operative positions, power means for causing reciprocations of the presser member toward and from the cutting bed, power means for

swinging the presser member laterally over the cutting bed, a manually operable member mounted on the presser member to control the pressure applying operations of the 5 presser member, and a second manually operable lever to control the power means for swinging the presser member laterally over the work supporting bed.

58. In a machine of the class described, a 10 work supporting bed, a presser member, a post upon which the presser member is rotatably mounted, and means for automatically moving the presser member out of operative position immediately after a pressure applying operation.

59. In a machine of the class described, a 15 work supporting member, a presser member arranged to cooperate with the work supporting member, a post upon which the 20 presser member is rotatably mounted for movement laterally over the die, and means operable to act upon the presser member to prevent said member from tipping away from the bed during a pressure applying 25 operation.

60. In a machine of the class described, a 30 work supporting member, a presser member arranged to co-operate with the work supporting member, a post upon which the 35 presser member is rotatably mounted for movement laterally over the die, and means for locking the rotatable presser member against lateral movement just as it is about to strike the die in a pressure applying 40 operation.

61. In a machine of the class described, a 45 work supporting member, a presser member arranged to co-operate with the work supporting member, a post upon which the 50 presser member is rotatably mounted for movement laterally over the die, and a power operated slide for locking the rotatable presser member against lateral movement just as it is about to strike the die in a pressure applying operation.

62. In a machine of the class described, a 55 work supporting member, a presser member arranged to co-operate with the work supporting member, a post upon which the 60 presser member is rotatably mounted for movement laterally over the die, and a slide member arranged parallel with the post for locking the presser member against rotation just as it is about to strike the die during a pressure applying operation.

63. In a machine of the class described, a 65 cutting bed, a presser member, power means for causing movement of the presser member in either direction to place the presser member in different operative positions over the cutting bed, a lever mounted below the presser member to turn on a horizontal axis for controlling said power means, and connections between said means and the lever so arranged that movement of the lever in

a given direction is followed by movement of the presser member in the same direction.

64. In a machine of the class described, a 70 cutting bed, a presser member, power means for causing lateral movement of said presser member, power means for causing pressure applying movement of the presser member, said power means being independently operable with respect to each other, and a single means mounted below the presser member for controlling both said power means.

65. In a machine of the class described, a 75 cutting bed, a presser member, power means for causing movement of the presser member into and out of selected positions over the cutting bed, power means for moving the presser member toward and from the bed, and means located at one side of the cutting bed in a position accessible to the 80 operator for controlling either of said power means independently of the other to effect movement of the presser member at the will of the operator.

66. In a machine of the class described, a 85 presser members relatively reciprocable toward and from each other in pressure applying operations and relatively movable laterally into and out of operative position, power means for causing such relative lateral movement of the presser members, and means, comprising a stop controlled by said first-mentioned means, for limiting the said relative movement of the presser members.

67. In a machine of the class described, a 90 work supporting bed, a presser member, power means for causing movement of the presser member into and out of selected positions over the bed, power means for moving the presser member toward and from the bed in pressure-applying operations, and means located below the plane of the supporting surface of the bed and in a position accessible to the operator for controlling the 95 first-mentioned power means to effect lateral movement of the presser member at the will of the operator independently of a pressure-applying operation of the machine.

68. In a machine of the class described, a 100 presser members relatively movable into and out of operative position with respect to each other, means for causing such relative movement of the presser members, a stop located on the frame of the machine, and a second stop associated with said means and 105 movable during the relative movement of the presser members and arranged to co-operate with the first mentioned stop to limit such relative movement of the presser members.

69. In a machine of the class described, a 110 work supporting bed, a presser member movable laterally over the bed into and out of various selected positions over the work support on the bed, a stop located on the 115 frame of the machine, a second stop movable 120

125

130

during the movement of the presser member and through distances directly proportional to the distance traveled by the presser member to co-operate with the first mentioned stop in limiting movement of the presser member in one direction, and means for operatively connecting the second stop with the presser member.

70. In a machine of the class described, a work supporting bed, a presser member movable laterally over the bed into and out of various operative positions with respect thereto, a stop located on the frame of the machine, a second stop arranged to co-operate with the first mentioned stop to limit the movement of the presser member, and a cable for operatively connecting the second mentioned stop with the presser member.

71. In a machine of the class described, a work supporting bed, a presser member movable toward and from the bed in pressure applying operations and also laterally over the bed into and out of various selected operative positions with respect thereto, power means comprising a cable for moving the presser member laterally of the bed, a stop located on the frame of the machine, a second stop mounted for movement toward and from the first mentioned stop, and a cable connecting the presser member with the second stop and so arranged that the presser member is held against movement

when the stops come into contact with each other.

72. In a machine of the class described, a work supporting bed, a presser member movable toward and from the bed in pressure applying operations and also laterally over the bed into and out of selected operative positions with respect thereto, power means for causing the presser member to approach and recede from the bed, power means for moving the presser member laterally over the bed, a stop mounted on the frame of the machine, and a second stop operative by the last mentioned power means in co-operative relation to the first mentioned stop to limit the movement of the presser member.

73. In a machine of the class described, a work supporting bed, a presser member, power means for causing movement of the presser member into and out of selected positions over the bed, power means for moving the presser member toward and from the bed in pressure-applying operations, and an upright lever located at one side of the bed and in a position accessible to the operator for controlling the power means to effect movements of the presser member in amounts determinable by the operator.

In testimony whereof I have signed my name to this specification.

MILTON H. BALLARD.
